Northrop Corporation, Beverly Hills, Calif., a cor-
poration of California

Filed Sept. 3, 1968, Ser. No. 13,374

Term of patent 14 years

Int. Cl. D15—05

U.S. Cl. D55—1

*Fig. 3**Fig. 4*FIGURE 1 is a three-quarter perspective view of a trimmer for lead wires of printed circuit boards embodying my new design.

FIGURE 2 is a right end view;

FIGURE 3 is a top view; and

FIGURE 4 is a bottom view thereof.

The circular perforations on the plate members on either end of the trimmer for lead wires of printed circuit boards in FIGS. 1 and 2 are representative of the appearance of the plate members over their entire area.

I claim:

The ornamental design for a trimmer for lead wires of printed circuit boards, substantially as shown and described.
